CONVEYER

Elmer F. Seibel, Erie, Pa., assignor, by mesne assignments, to The Standard Stoker Company, Inc. (1922), New York, N. Y., a corporation of Delaware

Application February 20, 1934, Serial No. 712,099
Renewed October 21, 1937

4 Claims. (Cl. 198—15)

This invention, which relates to a conveying system and especially to the fuel conveying system of stokers, has for its principal object the improvement of a stoker conduit by constructing the same in a plurality of separable sections to the end that worn or defective sections may be conveniently renewed.

A more specific object of this invention resides in the provision of an improved stoker conduit of elbow formation comprising an upturned section and a vertically split horizontal portion including a pair of interfitted sections each secured to said upturned section.

It is a further object of this invention to provide in a conveyer conduit having a conveyer screw rotatably mounted therein, a detachable conduit element intermediate the ends of the conveyer conduit and embracing the conveyer screw, said conduit element including a plurality of interfitted sections, each of which is rigidly but detachably secured at its opposite ends to adjacent portions of the conveyer conduit, the interfitting sections being so constructed that any section may be easily removed without disturbing other parts of the conveyer conduit and without removing the conveyer screw from its position in the conduit.

In carrying out this last object, the detachable conduit element is split vertically into a pair of sections, one section having a key and groove arrangement opening upwardly and the other section having a complementary key and groove arrangement opening downwardly; the key of one section engaging the groove of the other section, such engagement of the grooves being accomplished without removing the screw from the conduit.

To those familiar with conveyer systems, other objects and advantages which are inherent in my construction will become apparent as the following specification is read in connection with the accompanying drawings, in which,

Figure 1 is a central vertical longitudinal section of a portion of a locomotive, showing the invention in position thereon;

Figure 2 is a sectional view taken on the line 2—2 of Figure 3;

Figure 3 is a sectional view taken on the line 3—3 of Figure 2;

Figure 4 is an isometric view of the improved elbow with one section thereof removed;

Figure 5 is an isometric view of the elbow section removed in Figure 4, and

Figure 6 is a view similar to Figure 3 showing a modification of the invention.

In the "Standard Type B" locomotive stoker, for which my invention has been particularly devised, the conduit which is disposed on the locomotive terminates in an angular member or elbow adapted to turn or direct the fuel upwardly as it is conveyed forwardly by the conveyer screw. The forward end of this conveyer screw is disposed at a predetermined position in the elbow and cooperates with the walls of the elbow and the conduit thereabove to force the fuel upwardly to a point of distribution. From actual experience, it has been found that when fuel is elevated in this manner, the conveyer screw bears against one upper side portion of the elbow conduit, dependent upon the direction of rotation of the screw. Thus, when viewed in the direction of fuel flow, if the conveyer screw turns counterclockwise, it will bear against the upper left side of the conduit, and vice versa.

This condition causes excessive wear of the elbow conduit at the above described portion thereof, and hence frequent replacements of the elbow must be made. Since the elbow of the stoker extends from beneath the firebox to a point exterior thereof and is otherwise associated with parts of the stoker and locomotive in intimate structural relation, its replacement is very difficult and removes the locomotive from service for several days when such repairs are being made. With the use of the present construction, this troublesome condition is obviated by an arrangement whereby the worn portion of the elbow may be easily removed within a few hours, and accordingly this forms a still further object of this invention.

Referring now to the preferred form of my invention as illustrated in Figures 1 to 5 inclusive, the locomotive is shown at 10 and includes frames such as 11 above which is mounted the boiler 12 having a firebox 13. The boiler 12 includes a hollow water leg 14 forming the backwall of the firebox and a mudring 15 which serves as a foundation for the firebox and also as a support for the grates 16. An expansion plate 17 is secured at one end to the frame 11 and at its opposite end to the mudring 15, forming a flexible support for the rearward portion of the boiler.

The stoker in which my invention is embodied comprises a horizontal conduit 18 at one end rigidly secured to the frame 11 as at 19 and also 50 flexibly connected as at 20 to a tubular conduit 21 which leads forwardly from a source of fuel supply on the tender (not shown). At its opposite end, the horizontal conduit 18 is flanged as shown at 18a and terminates rearward of and 55

- below the mudring 15. An elbow conduit, generally indicated by E is attached to the horizontal conduit 18, in a manner which will be fully described, and extends beneath the mudring 15 and the firebox 13. The forward portion of the elbow conduit E opens upwardly and is provided with a counter-bored portion 23 forming a seat for the core tube 24 which extends upwardly through and above the grates 16.
- 10 The grated wall 25 protects the core tube 24 from the intense heat in the firebox. A conveyer screw 26 leads forwardly from the tender and terminates in the elbow conduit E at a point therein which may be defined as one which permits the screw to elevate fuel upwardly through the core tube 24 without packing. As the fuel emerges from the mouth 27 of the core tube, it is scattered over the grates 16 by blasts of pressure fluid discharged through the orifices 28 of 20 the jet head 29.

The stoker construction described thus far is of conventional form and will be recognized by those familiar with the art as the well known "Standard Type B" locomotive stoker. My present invention is chiefly concerned with the structural formation of the elbow conduit E and its relation with associated parts of the locomotive and stoker, and this construction will now be described with more particularity.

- 30 This elbow conduit includes the upturned curved section 30 and the vertically split conduit 31 comprising sections 32 and 33. Foot members 34 are formed with the curved section 30 and these are bolted securely to a bracket 35 carried by the locomotive frame 11.

The longitudinal ends of each section 32 and 33 are provided with lateral flanges such as 32a, 32b and 33a, 33b, respectively, while the forward end of the conduit 18 and the horizontally opened rearward end of the curved section 30 are also flanged as at 18a and 30a, respectively. As clearly shown in the drawings, the flanged ends of the vertically split conduit 31 fit flush against the corresponding flanges of the conduit 18 and the curved section 30, respectively, and bolts such as 36 securely connect these flanges.

With the flights 37 of the conveyer screw 26 wound in the direction shown, the screw bears against the upper portion 38 of the section 32 when fuel is being elevated through the conduit 24. This causes a lateral and rearward thrust on the section 32 and in order that this thrust will not cause a separation of the sections 32 and 33, and also so that the entire thrust load may not be imposed on the bolts 36 on the one side of the conduits 30, 18, the sections 32, 33 are interfitted in a novel manner.

Since the section 33 will be less frequently replaced than section 32, this first named section is provided with an upwardly directed key 39 and groove 40, there being two of such key and groove arrangements, one at the upper free end and another at the lower free end of the section 33. The corresponding free ends of the section 32 are therefore provided with downwardly directed keys 41 and grooves 42. Preferably, the keys and grooves are machined to a close tolerance so that the joint between the sections 32, 33 will be firm and one which forms a centering or mastering means between these sections. In Figure 6 I have shown a modification of this feature of my invention wherein the interfitting keys and grooves 43, 44, 45 and 75 46 of the sections 32, 33 respectively are not

machined but cast to the required configuration and then dressed with an emery wheel to size. This type of key and groove arrangement can be used with equal success providing that a close fit between the interfitted elements of each section is maintained. By the use of a jig or other fixture, it is practical to grind these cast keys and grooves to accurate dimensions.

It will be observed from Figure 3 that the outer diameter of the conveyer screw 26 is somewhat less than the inner diameter of the conduit 31, and also that this difference in dimensions is greater than the depth of engagement between the keys and grooves of the sections 32 and 33. Thus, whenever the section 32 has been worn excessively, the bolts which hold this section to the curved section 30 and the conduit 18 are removed and then the stoker mechanic lifts the section 32 upwardly, disengaging this section from the section 33, which is still in its normal position. The conveyer screw 26 permits of such upward movement because it is also capable of upward movement. Likewise, when applying a new section 32, the mechanic places the lower edge of the section against the bottom of the screw flight 37, and lifts the section and screw whereby the key of one section will engage the groove of the other section. By the use of the machined key and groove arrangement the bolt holes 36a of the various flanges will always be in alignment, thereby enabling the mechanic to insert the bolts 36 with considerable ease.

I have found that the life of the renewable sections 32, 33 is increased materially by chilling their respective upper portions 38 and 47. Care should be taken, however, that the chilled portion does not extend too close to the machined key and groove arrangement because this would result in tool breakage during the machining operation. In the actual construction of this device the edge 48 of the upper groove 42 which is formed in the section 32 is not machined and this groove is slightly wider than the width of the engaging key 39 of section 33. This has been found necessary because of the difficulty in controlling the extent of the chill.

Although my invention has been described in connection with but one type of stoker, it is obvious that the features of novelty which I have devised are capable of use with other forms of stokers as well as with conveyers in general. It will also be apparent that by my construction, the more or less permanently mounted conduits 18 and 30 are not disturbed when either of the sections 32 or 33 is renewed, and that the conveyer screw 26 which is embraced by these sections may also be maintained in its position when such repairs are being made.

I claim:

1. In combination with a locomotive having a frame and a firebox above said frame, said firebox having a rear wall provided with a foundation ring, a stoker including a conduit at one end receiving fuel from a source of supply and at its opposite end delivering the fuel into the firebox, a conveyer screw rotatably mounted in said conduit, said conduit having a detachable portion intermediate its ends between the foundation ring and the frame split into a pair of sections, said detachable portion embracing at least a portion of the conveyer screw and having internal dimensions greater than the diameter of the conveyer screw embraced by said detachable portion, a key and groove arrangement in each 75

of said sections, the key and groove of one section being interfitted respectively with a groove and key of the other section, the depth of the key and groove engagement being no greater than 5 the difference between the internal dimensions of the detachable portion and the diameter of the conveyer screw therein, and means for securing said sections to said conduit.

2. In combination with a locomotive having a 10 frame and a firebox above said frame, said firebox having a rear wall provided with a foundation ring, a stoker including a conduit at one end receiving fuel from a source of supply and at its 15 opposite end delivering the fuel into the firebox, a conveyer screw rotatably mounted in said conduit, said conduit having a detachable portion intermediate its ends between the foundation ring and the frame split into a pair of sections, said 20 detachable portion embracing at least a portion of the conveyer screw and having internal dimensions greater than the diameter of that portion 25 of the conveyer screw embraced by said detachable portion, a key and groove arrangement formed at the free edges of each section and extending longitudinally of said detachable portion, the grooves of one section opening in one direction and the grooves of the other section opening in the opposite direction, the keys and grooves of one section being interfitted with the respective 30 grooves and keys of the other section, the depth of the key and groove engagement being no greater than the difference between the internal dimensions of the detachable portion and the diameter of the conveyer screw therein, and means 35 for securing each of said sections to said conduit and said upturned curved portion.

3. In combination with a locomotive having a frame and a boiler firebox above said frame, said firebox having a rear wall provided with a foundation ring, a stoker including a conduit rigidly 40 secured to said frame, said conduit terminating adjacent the firebox and at its end remote from the firebox arranged to receive fuel from a source of supply, an elbow conduit at the terminal end of the conduit, said elbow conduit including an

upturned curved portion directed toward the firebox and a detachable portion between the foundation ring and the frame split into a pair of sections, said upturned portion being rigidly secured to said frame, a conveyer screw rotatably mounted in said conduit and having at least a portion thereof extending freely within said detachable portion, a key and groove arrangement formed at the free edges of each section and extending longitudinally of said detachable portion, the 10 grooves of one section opening in one direction and the grooves of the other section opening in the opposite direction, the keys and grooves of one section being interfitted with the respective 15 grooves and keys of the other section, the depth of the key and groove engagement being no greater than the difference between the internal 20 dimensions of the detachable portion and the diameter of the conveyer screw therein, and means for securing each of said sections to said conduit and said upturned curved portion.

4. In combination with a locomotive having a frame and a firebox above said frame, said firebox having a rear wall provided with a foundation ring, a stoker including a conduit rigidly secured to said frame, said conduit terminating adjacent the firebox and at its end remote from the firebox arranged to receive fuel from a source of supply, an elbow conduit at the terminal end of the conduit, said elbow conduit including an 30 upturned curved portion directed toward the firebox and a detachable portion between the foundation ring and the frame split vertically into a pair of semi-cylindrical sections, said upturned portion being rigidly secured to said frame, a conveyer screw rotatably mounted in said conduit and having at least a portion thereof extending freely within said detachable portion, the longitudinal meeting faces of said sections being provided with interengageable tongues and grooves, 40 and means for securing each of said sections to said conduit and said upturned curved portion.

ELMER F. SEIBEL.
